UNITED STATES PATENT OFFICE.

GEORGE W. FORTIER, OF GRAND RAPIDS, MICHIGAN.

NUT-LOCK.

SPECIFICATION forming part of Letters Patent No. 678,775, dated July 16, 1901.

Application filed September 24, 1900. Serial No. 31,001. (No model.)

To all whom it may concern:

Be it known that I, GEORGE W. FORTIER, a citizen of the United States, residing at Grand Rapids, in the county of Kent and State of Michigan, have invented certain new and useful Improvements in Nut-Locks, of which the following is a specification.

My invention relates to improvements in nut-locks; and its object is to provide a nut-lock that, while perfectly reliable as a nut-lock, may be readily unlocked to remove the nut when desired. I attain this object by the mechanism illustrated in the accompanying drawings, in which—

15 Figure 1 is a bottom plan of a nut, showing my lock in place. Fig. 2 is an elevation of a nut and washer cut away at $x x$ to show the application of the lock, and Fig. 3 is a top plan of the washer.

20 Similar letters refer to similar parts throughout the several views.

A represents an ordinary square nut into which I form a slot C' for the reception of a pawl C, for which I form a pivot-bearing on 25 the nut by striking an offset from the nut each side of and into the slot, as indicated at c in Figs. 1 and 2, and make a corresponding notch in the lower edge of the pawl C, as at c', which fits over the offsets and forms the 30 bearing for the pawl. To actuate the pawl, I place a spring, as E, between the upper edge of the pawl and the top of the slot. I form a small notch e in the upper edge of the pawl just back of the bearing, so that the spring 35 will enter and avert the danger of sliding out of place. The bearing of the spring on the pawl is so adjusted that the pressure upon the end b' is much greater than that back of the bearing, and the end may be raised and 40 lowered without danger of raising the pawl from its bearing on the offsets c.

The washer, which forms an important element in this invention, is formed with a series of serrations b, designed to be directly in the path of the pawl C, so that when the nut 45 is turned to secure an object to place the point of the pawl will engage the serrations and prevent the nut from turning backward until the pawl has been raised from such contact, which may be done in several ways; 50 but I find the most available way to be to enter a short wedge, as D, between the back end of the pawl and the top of the slot. I prefer the use of the wedge, as it can be driven in flush with the surface of the side of the 55 nut and will not interfere with the use of a wrench for manipulating the nut.

I find the use of a downwardly-projecting point b" on the lower surface of the washer a great advantage for use upon a wood base. 60

Having thus fully described my invention, what I claim as new, and desire to secure by Letters Patent, is—

In combination with a washer having a serrated surface, a nut having a slot formed in 65 its lower surface and extending tangentially from near the center orifice of the nut to the side thereof, offsets struck from the nut in each side of the slot, a pawl having a notch in the edge engaging said offsets and forming a 70 pivot-bearing for the pawl, and an actuating-spring above the pawl, substantially as and for the purpose set forth.

Signed at Grand Rapids, Michigan, September 14, 1900.

GEO. W. FORTIER.

In presence of—

JAS. E. BAKER,
I. J. CILLEY.
